UNITED STATES PATENT OFFICE.

EDWIN WILDT, OF LEICESTER, ENGLAND, ASSIGNOR TO WILDT AND COMPANY, LIMITED, OF LEICESTER, ENGLAND, A BRITISH COMPANY.

STOP MOTION FOR YARN, THREAD, AND LIKE WINDING MACHINES.

Application filed September 24, 1924. Serial No. 739,468.

To all whom it may concern:

Be it known that I, EDWIN WILDT, a subject of the King of Great Britain, residing at Leicester, in the county of Leicester, England, have invented new and useful Improvements in or Relating to Stop Motions for Yarn, Thread, and like Winding Machines, of which the following is a specification.

10 The invention relates to machines for winding yarns, threads and the like from hanks on to bobbins or like members and concerns those of the kind provided with a stop motion for automatically stopping rotation of the bobbin or equivalent when the tension on the winding yarn or thread is abnormally increased.

15 In machines of this kind the hank, from which the yarn or thread is drawn for winding, is usually carried upon what is termed a "swift". This carrier is mounted in a rotatable manner and is rotated by the yarn being drawn therefrom. When the stop motion becomes effective and arrests rotation of the bobbin or other device upon which the yarn is being wound there is a tendency for the swift or hank carrier, owing to the momentum set up by its rotation, to overrun i. e. continue to rotate 20 after the bobbin has stopped. This is liable to drag or ravel the yarn and sometimes to such an extent as to break it.

25 The object of the invention is to provide means which will operate in conjunction with the stop motion to arrest rotation of the swift or hank carrier when said stop motion operates to arrest rotation of the bobbin or other device upon which the yarn or thread is being wound.

30 By positively arresting the rotation of the swift when the winding spindle stops, overrunning of the swift is prevented. This is an important improvement in connection with the winding of yarns by reason of the fact that the elimination of the possibility 35 of overrun enables the machine to be driven at a much higher speed than heretofore, consequently the yarn can be more quickly wound and the output of the machine increased.

35 According to the invention a brake or other suitable stopping device is provided for arresting rotation of the swift or hank carrier said brake or device being operable

40 by intermediate connections actuated by a part of the stop motion of the winding machine.

45 In the preferred arrangement the brake or stopping device is normally held out of action by a spring or weight and the operating connections are acted upon by the member of the stop motion which is controlled by the winding yarn.

50 In further describing the invention reference will be hereinafter made to the accompanying drawings wherein,

55 Figure 1 is a side elevation partly in section, and

60 Figure 2 is a rear elevation of a convenient embodiment of the invention, showing the brake device and the stop motion in the inoperative position.

65 Figure 3 is a view similar to Figure 1, but shows the brake and the stop motion in the operative position, and

70 Figure 4 is a side elevation partly in section for partly releasing the brake device and stop motion after the operation thereof, to permit of the bobbin spindle being rotated by hand as will be hereinafter described.

75 According to the illustrated embodiment of the invention, a brake shoe 1 pivotally mounted on the underframe member 2 which carries the swift or hank carrier 3 is controlled by a tension spring 4 and normally held clear of a hub 5 on the swift or hank carrier. The brake shoe 1 is pressed into contact with the hub by a push rod 6 slidable in lugs 7 on the member 2, one 80 end of which push rod acts upon said shoe the other end being acted upon by a lever or bar 8 also pivoted on the under frame member 2. This bar or lever is moved by a suitable part of the stop motion. For example, the mechanism constituting the present invention may be used in conjunction with a stop motion of the kind wherein a lever held in normal position by a spring or weight is operated by abnormal tension of the yarn to stop rotation of the bobbin spindle. An arrangement of this nature is illustrated in the accompanying drawings. In said arrangement a lever 9 is fulcrumed upon a bracket 10 attached to a cross member 11 on the machine frame and has connected therewith an arm 12 carrying a roller 13 or equivalent adapted in normal

position to engage one end of a lift lever 14, pivoted on the bracket 10, so as to maintain the other end of said lever out of engagement with the usual driver disc 15 on the bobbin spindle 16 against the action of a spring 17, or equivalent. The yarn or thread represented by the dot and dash line 18 passes from the swift 3 over a bar 19 through a knot plate 20 round guide pulleys 21 and 22 on the lever 9 and a pivoted arm 23 respectively and thence to the bobbin 24. Referring now to Figure 3, if for any reason the tension of the yarn becomes abnormal the lever 9 is pulled downwards thereby breaking the engagement between the roller 13 and the lift lever 14 whereupon the lever 9 falls and strikes the pivoted lever or bars 8 which through the medium of the push rod 6 applies the brake shoe 1 to the hub 5 of the swift or hank carrier to arrest rotation of the latter. At the same time the lift lever 14 is actuated by its spring 17 to disengage the disc 15 from the usual driving wheel 25 and lifts it into contact with a brake pad 26 on the bracket 10 thereby stopping the winding spindle.

If desired, the aforesaid brake mechanism may be used in conjunction with the mechanism described in British specification No. 28480 of 1913, the yarn operated lever 1 referred to in said specification being arranged to strike and move the aforesaid lever or bar 8 to apply the brake 1 in the manner just described.

In order to enable the swift or hank carrier 3 and the bobbin spindle 16 to be rotated by hand, if necessary for re-threading or other purposes after the operation of the stop motion and the brake mechanism as aforesaid, we may provide, in combination with said brake mechanism and stop motion, means for effecting a partial release of the same. Conveniently, such means comprise a handle 27 secured to a spindle 28 rotatable in the bracket 10 and having fast thereon a lever formed by fingers 29 and 30. The finger 29 engages the lever 9 while the finger 30 engages the adjacent end 50 of the lift lever 14 when the handle 27 is actuated as shown in Figure 4, with the lever 9 and the lift lever 14 in the position shown in Figure 3. Thus the lever 9 may be raised slightly to partly release the brake shoe 1 and at the same time the lever 14 may be partly released to allow the disc 15 to move sufficiently to clear the brake pad 26. During the movement of the handle 27 the finger 30 enters a recess 31 in the lift lever 14 thus arresting the movement of the latter so as to prevent said disc from engaging the driving wheel 25.

The details of construction may be varied without departing from the scope of the invention.

What I claim then is:—

1. In a yarn winding machine of the kind described, a brake arrangement for arresting the rotation of the swift, comprising a brake device, means for normally holding the same inoperative, and operating connections between said device and a yarn controlled lever of the stop motion of the machine which is held in normal position by suitable means and actuated to render the stop motion active by abnormal tension of the yarn, said connections being operated to apply the brake by the direct action thereon of the lever when the latter is actuated. 50

2. In a yarn winding machine of the kind described a brake arrangement for arresting the rotation of the swift, comprising a brake device, a spring for normally holding the same inoperative, and operating connections between said device and a yarn controlled lever to stop motion of the machine which is held in normal position by a spring and actuated to render the stop motion active by abnormal tension of the yarn, said connections being operated to apply the brake by the direct action thereon of the lever when the latter is actuated. 85

3. In a yarn winding machine of the kind described, a brake arrangement for arresting the rotation of the swift, comprising a brake device, a spring for normally holding the same inoperative, and operating connections between said device and a yarn controlled lever of the stop motion of the machine which is held in normal position and actuated to render the stop motion active by abnormal tension of the yarn, said connections being operated to apply the brake by the direct action thereon of the lever when the latter is actuated. 130

4. In a yarn winding machine of the kind described, a brake arrangement for arresting the rotation of the swift, comprising a pivoted brake shoe adapted to engage a hub on the swift, a spring for normally holding said shoe clear of the hub, a push rod for acting upon the brake shoe and a pivoted bar for acting upon the push rod, said bar being acted upon by a yarn controlled lever of the stop motion of the machine so as to cause the brake shoe to be applied to the hub when the lever is actuated to render the stop motion active. 110

5. In a yarn winding machine of the kind described, a brake arrangement for arresting the rotation of the swift, comprising a pivoted brake shoe adapted to engage a hub on the swift, a spring for normally holding said shoe clear of the hub, a push rod for acting upon the brake shoe, and a pivoted bar for acting upon the push rod, said bar being engaged by a yarn controlled lever of the stop motion of the machine which is held in normal position 125 130

by a spring and actuated to render the stop motion active and to put the brake shoe into operation by abnormal tension of the yarn.

6. In a yarn winding machine of the kind described, a vertical bobbin spindle, a friction disc thereon, a wheel for driving the disc, a spring controlled lift lever for engaging one side of said disc, a brake pad on the opposite side of the disc, but normally clear of same, a yarn controlled lever for normally holding the lift lever clear of the friction disc and actuated by abnormal tension of the yarn to release said lift lever so that it lifts the friction disc off the driving wheel and into contact with the brake pad to stop rotation of the bobbin spindle, a swift, a brake device for the swift, and connections arranged between said device and the yarn controlled lever and acted upon by said lever, when the latter is actuated, for putting the brake device into operation.

7. In a yarn winding machine of the kind described, a vertical bobbin spindle, a friction disc thereon, a wheel for driving said disc, a lift lever for engaging one side of said disc, a brake pad on the opposite side of the disc, but normally clear of same, a spring normally tending to cause said lift lever to disengage the disc from the driving wheel and press it into contact with the brake pad to stop rotation of the bobbin spindle, a yarn controlled lever for normally holding the lift lever clear of the friction disc and movable downwards by abnormal tension of the yarn to release said lever, a swift, a pivoted brake shoe for engaging a hub on the swift, a spring for normally holding said shoe clear of the hub, a push rod for acting upon the brake shoe and a pivoted bar for acting upon the push rod said bar being actuated by the yarn controlled lever, upon the downward movement of the latter, to apply the brake shoe to the hub of the swift.

8. In a yarn winding machine of the kind described, a vertical bobbin spindle, friction driving means for the spindle, a brake pad, a spring actuated lift lever for rendering said driving means inoperative and applying the brake to stop rotation of the bobbin spindle, a yarn controlled lever, an arm connected thereto and a roller in the arm for normally holding the lift lever out of action and operable by abnormal tension of the yarn for releasing said lever, a swift, a spring controlled brake shoe for arresting the rotation of said swift, a push rod for acting upon the brake shoe, and a pivoted bar adapted to act upon the push rod, said pivoted bar being actuated by the yarn controlled lever, when the latter is operated, to put the brake shoe into operation.

9. In a yarn winding machine of the kind

described, a brake arrangement for arresting the rotation of the swift comprising a brake device and operating connections arranged between said device and a yarn controlled lever of the stop motion of the machine whereby said connections are operated to apply the brake when the stop motion operates, and means for effecting a partial release of the brake device and stop motion after the operation thereof.

10. In a yarn winding machine of the kind described, a brake arrangement for arresting the rotation of the swift comprising a brake device, a spring for normally holding the same inoperative, and operating connections between a yarn controlled lever of the stop motion of the machine which is held in normal position by a spring and actuated to render the stop motion active by abnormal tension of the yarn, said connections being operated to apply the brake by the direct action thereon of the lever, when the latter is actuated, and means for effecting a partial release of the brake device and stop motion after the operation thereof.

11. In a yarn winding machine of the kind described, a brake arrangement for arresting the rotation of the swift, comprising a pivoted brake shoe, adapted to engage a hub on the swift, a spring whereby said shoe is normally held inoperative, a push rod for acting upon the brake shoe, a pivoted bar for acting upon the push rod, said bar being acted upon by a yarn controlled lever of the stop motion of the machine so as to cause the brake shoe to be applied to the hub when the lever is actuated to render the stop motion active, and means for effecting a partial release of the brake device and stop motion after the operation thereof.

12. In a yarn winding machine of the kind described, a brake arrangement for arresting the rotation of the swift, comprising a pivoted brake shoe adapted to engage a hub on the swift, a spring for normally holding said shoe clear of the hub, a push rod for acting upon the brake shoe, a pivoted bar for acting upon the push rod, said bar being engaged by a yarn controlled lever of the stop motion of the machine which is held in normal position by a spring and actuated to render the stop motion active and to put the brake shoe into operation by abnormal tension of the yarn, and manually operable means for effecting a partial release of the brake shoe and stop motion after the operation thereof.

13. In a yarn winding machine of the kind described, a vertical bobbin spindle, a friction disc thereon, a wheel for driving the disc, a spring controlled lift lever for engaging one side of the disc, a brake pad on the opposite side of the disc but normally clear

- of same, a yarn controlled lever for normally holding the lift lever clear of the friction disc and actuated by abnormal tension of the yarn to release said lift lever so that it lifts the friction disc off the driving wheel and into contact with the brake pad to stop rotation of the bobbin spindle, a swift, a brake device for the swift, connections, arranged between said device and a yarn controlled lever and acted upon by said lever, when the latter is actuated, for putting the brake device into operation, and a hand lever and a member associated therewith for moving the yarn controlled lever and the lift lever after the operation thereof for partly releasing the brake device and the stop motion.
14. In a yarn winding machine of the kind described, a vertical bobbin spindle, a friction disc thereon, a wheel for driving said disc, a lift lever for engaging one side of the disc, a brake pad on the opposite side of the disc, but normally clear of same a spring whereby the lift lever is moved to disengage the disc from the driving wheel and press it into contact with the brake pad to stop rotation of the bobbin spindle, a yarn controlled lever for normally holding the lift lever clear of the friction disc and movable downwards by abnormal tension of the yarn to release said lever, a swift, a pivoted brake shoe for engaging a hub on the swift, a spring whereby said shoe is normally held clear of the hub, a push rod for acting upon the brake shoe, a pivoted bar for acting upon the push rod, said bar being actuated by the yarn controlled lever, upon the downward movement of the latter, to apply the brake shoe to the hub of the swift, a hand lever and a member connected thereto and movable thereby for engaging and moving the yarn controlled lever and the lift lever slightly after the operation thereof, to partly release the brake shoe and the friction disc.
15. In a yarn winding machine of the kind herein described, a vertical spindle friction driving means for the spindle, a brake pad, a spring actuated lift lever for rendering said driving means inoperative and applying the
- brake to stop rotation of the bobbin spindle, a yarn controlled lever, an arm connected thereto and a roller in the arm for normally holding the lift lever out of action and operable by abnormal tension of the yarn for releasing said lever, a swift, a spring controlled brake shoe for arresting the rotation of the swift, a push rod for acting upon the brake shoe, a pivoted bar adapted to act upon the push rod, said bar being actuated by the yarn controlled lever, when the latter is operated, to put the brake shoe into operation, a pivoted handle, and a lever connected thereto and operable thereby for lifting the yarn controlled lever and lowering the lift lever slightly after the operation thereof to partly release the brake shoe and the friction disc.
16. In a yarn winding machine of the kind described, a brake arrangement for arresting the rotation of the swift comprising a brake device, a spring for normally holding the same inoperative, and operating connections between said device and a yarn controlled lever of the stop motion of the machine which is normally held raised and is pulled downwards by abnormal tension of the yarn to render the stop motion active, said connections being operated to apply the brake as the result of the contact therewith of the lever when the latter falls.
17. In a yarn winding machine of the kind described a brake arrangement for arresting the rotation of the swift, comprising a brake device, a spring whereby said device is held inoperative, operating connections between the device and a yarn controlled lever of the stop motion of the machine which is normally held raised and is pulled downwards by abnormal tension of the yarn to render the stop motion active, said connections being operated to apply the brake as the result of the contact therewith of the lever when the latter falls, and means for effecting a partial release of the brake device and the stop motion after the operation thereof.

In testimony whereof I have signed my name to this specification.

EDWIN WILDT.
